United States Patent Office

Des. 188,607

Patented Aug. 16, 1960

188,607

TABLE

John J. Lubberts and Lambert J. Mulder, Grand Rapids, Mich., assignors to Tomlinson of High Point, High Point, N.C., a corporation of North Carolina

Filed Sept. 21, 1959, Ser. No. 57,632

Term of patent 14 years

(Cl. D33—14)

The figure is a perspective view of a table embodying our new design.

The article disclosed is symmetrical and the opposite sides are of the same appearance as that of the sides disclosed.

We claim:

The ornamental design for a table, substantially as shown and described.
